UNITED STATES PATENT OFFICE.

WILLIAM L. CARTER, OF CEDAR FALLS, IOWA.

FURNACE.

SPECIFICATION forming part of Letters Patent No. 459,675, dated September 15, 1891.

Application filed March 19, 1891. Serial No. 385,648. (No model.)

To all whom it may concern:

Be it known that I, WILLIAM L. CARTER, a citizen of the United States, residing at Cedar Falls, in the county of Black Hawk and State 5 of Iowa, have invented a new and useful Furnace, of which the following is a specification.

This invention relates to hot air furnaces; and the objects in view are to provide a furnace to consume a minimum amount of fuel 10 and yield a maximum amount of heat.

With the above objects in view the invention consists in certain features of construction hereinafter specified, and particularly pointed out in the claims.

15 Referring to the drawings, Figure 1 is a side elevation. Fig. 2 is a vertical longitudinal section. Fig. 3 is a partial horizontal section.

Like numerals of reference indicate like parts in all the figures of the drawings.

20 In practicing my invention I employ a conical shell 1, which at its lower end is provided with an internal flange or base-ring 2, having its inner edge downwardly turned or flanged, as at 3, while the upper end of the shell is

25 provided with a crown 4. The crown and the base-ring or internal flange 2 are provided along their outer edges with semicircular-shaped openings 5, which are connected by tubes 6, open at their upper and lower ends, 30 and therefore extending along the inner surface of the shell 1, where they may be acted upon by the products of combustion. The shell thus constructed is provided with a suitable fuel-opening 7, diametrically opposite

35 the same, with an uptake or pipe-opening 8, and the whole is seated upon a suitable base comprising the usual ash-pit 9. To the uptake or pipe-opening 8 is connected the lower end of a convoluted or coiled pipe 10, which

40 passes around the conical shell 1 and terminates in a chimney, into which the products of combustion pass after having passed through the pipe. At intervals below the termination of the pipe said pipe is tapped, and

45 branch pipes 11 pass into the chimney, and they, together with the end of the pipe, are provided with dampers 12. The entire furnace thus constructed is surrounded by a suitable jacket 13, to which are connected the 50 usual heat-pipes 14.

In operation the heat radiates from the pipe

10, the whole surface of which is inclosed by the jacket, and also radiates from the conical shell and its dome, and the cold air passes up through the hot-air pipes 6 and is warmed by 55 radiation and emptied into the jacket, from which it passes off through the heat-pipes to the points of use. It will be observed that by opening all of the dampers 12 the draft is increased to the utmost and the fire intensified, and by closing the drafts or one or more of them the fire is cooled or decreased, so that in this manner the heat may be regulated. Hand-holds 14 are provided with caps and located in each of the coils of the pipe 10, where- 60 by the coils may be readily cleaned of soot, dust, &c. The dome, being of frustum shape, throws the flues over the fire, and thus they are more directly exposed to the heat and radiate a greater amount of heat than if vertical. At the same time they and the coils are disposed in an inclined manner, and consequently offer but little obstruction to the free passage of heat therethrough.

Having described my invention, what I 75 claim is—

1. In a hot-air furnace, the combination, with the inner and outer shells, of a coiled pipe leading from the inner shell, coiled about the same and terminating in an uptake, and 80 a series of branch pipes located upon each coil and communicating with the uptake, substantially as specified.

2. The combination, with the outer shell, the heat-pipes connected therewith, and the 85 conical inner shell, of the pipe connected to the inner shell, coiled about the conical shell and projected through the outer shell, where it communicates with the chimney or uptake, and the series of branch pipes, one leading 90 from each coil and all provided with dampers, substantially as specified.

3. In a hot-air furnace, the combination, with the outer jacket and the inner conical shell provided with a perforated dome and at 95 its lower end a base-ring having openings corresponding to those in the dome, the pipes connecting said openings of the dome and ring, of a coiled pipe communicating with the inner shell and passed around the same and terminating in a chimney, substantially as 100 specified.

4. The combination, with the outer shell,
the heat-pipes connected therewith, and the
conical inner shell having a series of tubes
which are open at the top and bottom and
5 arranged along the inner side of the shell, of
the pipe connected to the inner shell, coiled
about the conical shell and projected through
the outer shell, where it communicates with
the chimney or uptake, and the series of
10 branch pipes, one leading from each coil and

all provided with dampers, substantially as
specified.

In testimony that I claim the foregoing as
my own I have hereto affixed my signature in
presence of two witnesses.

WILLIAM L. CARTER.
